Rud. P. Mockmerton
Letters Patent

The Schedule referred to in these Letters Patent and making part of the same containing a description in the words of the said Rud. P. Mockmerton himself of his improvement in the machine for planing boards, flooring, and other materials

It all to whom these presents shall come, Rud. P. Mockmerton of the City and State of New York, Greeting. Be it known that the said Rud. P. Mockmerton have invented, made and applied to the use of a new and useful improvement in the mode of planing boards, flooring and other materials by machinery or otherwise by means of a plane called the Vibrating Eccentric plane, specifically in the words following, viz. This improvement in the first place consists of a frame of wood or iron of about 14 ft in length and 3 ft in breadth standing on six legs about 5 ft high said frame to have about 4 to 6 cross pieces, or girders and otherwise sufficiently braced to make it firm and strong.

2^d Across the frame are placed four or more rollers, about five inches diameter, have a steel, or iron, turned true tree or more to make and the same above the plank the upper roller having pulleys of about 16 to 18 inches diameter or Coggs, which, attached to one end and are revolved by means of belts, or intermediate Coggs, wheels from a small pulley about six inches diameter or Coggs which on said shaft, or roller, move the frame, the upper rollers are held down by weights and levers, and the guides of which, are made more stable, so as to admit of different thicknesses of board or plank said frame has in the centre immediately beneath the planed a sea plate of iron or hard wood or rollers to support the plank to sprung the operation of the plane, on the said shaft there is a drum or Ratchett wheel with 16, 18, or 20, or more, of a drum about

of three inches diameter of a ratchett wheel about two feet six inches diameter; the arm to receive a pull from the first Motor - (which is a wheel of about thirty inches diameter placed above beneath the frame.) - and on the shaft of which is fixed a pulley of about twelve inches diameter. The power to the ratchett wheel can be attached to the crank shaft by the plane itself or by another wheel, may be most convenient to give it the forward and backward motion. -

3^d The plane is in form of a Zucchet suspended on a shaft or axis - supported by pillar blocks resting on galleries frames four feet high which said frames are firmly bolted in the frame of the machine and braced with a triangular brace - or otherwise.

4th The plane suspended by traces attached to eccentric - is a leg mount of a circle of about eight feet diameter and the length of plain Zucchet is about three feet, and of a shaft to which the material to be operated upon. It has five or more plane iron or cutters attached to its periphery set in a slanting position so as to make a smooth and clear cut and firmly fastened with three keys and regulated so as to be secure.

5th Motion is given to the plane by means of a shackle bar or connecting rod attached to the centre of the length of said plane and about six or nine inches from its periphery said connecting rod is attached by the other end to the end of the arm of the Fly wheel of about two feet six inches diameter - the shaft of said fly wheel about three and a half feet in length and 1 $\frac{1}{2}$ in diameter.

6th To the shaft or axis of plane are the small eccentric of about nine inches diameter to which the traces of the plane are attached by means of straps and short eccentric rods. The lowering and raising of the plane to accommodate different thicknesses of material to be planed is obtained by means of screw connecting the plane traces and eccentric rods.

7th The crank fastened to the plane arm and extending downwards in a line with the centre of the plane about two feet and three inches in length and attached to the connecting rod which at its other end

works in an eccentric about the first diameter (area to be buried according to length of Rank on plane axis) in fly wheel shaft.

6. The operation of the eccentrics in plane axis and in fly wheel shaft by means of the rack and the connecting rod give a vibratory & rectilinear motion to the plane by means of which the plane in its forward stroke cuts a part of its course in a straight line and the balance of the cut circular.

7. The side cutters for grooving and truing up them in their construction and mode of operation do not materially vary from those long in use or they may be made in principles analogous to those of the plane above described.

18. The Vibratory and rectilinear motion above mentioned may be obtained by various other means, viz by means of rack and pinion - by cams - by links - by parallel motion, &c. &c. to communicate the use in Steam Engines by sun and planet wheels, or by dropping the rear end of the plane by means of screws in the rear truss of the frame - but eccentrics as above described are judged preferable.

The said Reid R. Throckmorton claims particularly as his invention the peculiar construction of the plane and the manner of its motion being Vibratory and rectilinear & whereby the air is obtained by means of cutters in plane axis connected by crank and shackle bar with eccentric in fly wheel shaft. I do testimony that the above is a true Specification of my invention. I have hereunto set my hand the twenty-first day of May in the Year of our Lord one thousand eight hundred and thirty six.

Witness
